UNITED STATES PATENT OFFICE.

FRED A. SPRINGER, OF COSCOB, CONNECTICUT, ASSIGNOR TO MIANUS MANUFACTURING COMPANY, INC., OF COSCOB, CONNECTICUT, A CORPORATION OF CONNECTICUT.

DESIGN FOR CLOAKING.

45,897.

Specification for Design.

Patented June 2, 1914.

Application filed March 18, 1914. Serial No. 825,700. Term of patent 7 years.

To all whom it may concern:

Be it known that I, FRED A. SPRINGER, a citizen of the United States, residing at Cos Cob, in the county of Fairfield and State of Connecticut, have invented a new, original, and ornamental Design for Cloaking, of which the following is a specification, reference being had to the accompanying drawing, forming part thereof.

The figure is an elevation of a portion of fabric showing my new design.

I claim:—

The ornamental design for cloaking, as shown.

FRED A. SPRINGER.
